UNITED STATES PATENT OFFICE.

WILLIAM C. DEVEREAUX, OF DETROIT, MICHIGAN, ASSIGNOR TO FERRO STAMPING & MANUFACTURING COMPANY, OF DETROIT, MICHIGAN, A CORPORATION OF MICHIGAN.

DOOR LATCH.

Application filed August 23, 1922. Serial No. 583,922.

To all whom it may concern:

Be it known that I, WILLIAM C. DEVEREAUX, a citizen of the United States of America, residing at Detroit, in the county 5 of Wayne and State of Michigan, have invented certain new and useful Improvements in Door Latches, of which the following is a specification, reference being had therein to the accompanying drawings.

10 This invention relates to latches and is particularly applicable to latches for vehicle doors. One of the objects of the invention is the provision of a simple device for locking the bolt from longitudinal movement. 15 Another object is the provision of a rotatable hub member adapted to actuate the bolt, this hub member having an aperture therethrough for engagement by the operating shank of a door handle, the aperture having 20 a flaring entrance for facilitating the engagement of the operating shank therein. Further objects of the invention reside in the novel features of construction and combinations and arrangements of parts as more 25 fully hereinafter set forth.

In the drawings:

Figure 1 is a rear elevation of a door latch embodying my invention with the cover plate shown in dotted lines;

30 Figures 2 and 3 are cross sections respectively on the lines 2-2 and 3-3 of Figure 1;

Figure 4 is a horizontal cross section through a vehicle door showing my latch in plan.

35 1 is the case plate secured to the inner side 2 of the vehicle door and having the transverse flange 3 secured to the outer edge 4 of the vehicle door. 5 is the longitudinally movable bolt slidable upon the case plate 1 and having its nose projecting through the transverse flange 3. The inner end of this bolt slidably engages between the parallel struck out lugs 6 upon the case plate. 7 is a cover plate extending 40 parallel to the case plate 1 and having tongues extending through the transverse flange 3 and riveted thereon. This cover plate is secured to the case plate by means of the screws 8 passing through the cover plate 45 and threadedly engaging the spacers 9 which extend through the case plate and are riveted thereto. The case plate has the open-ended slot 10 extending longitudinally thereof and registering with the bolt 5.

11 is a lever extending substantially parallel to the cover plate and pivotally secured thereto at its lower end, this lever being engageable with the upwardly extending lug 12 upon the bolt 5 to move the bolt inwardly or retract the same. This lever 60 passes between the cover plate and the enlarged body of the bolt which is cut away for the passage of the lever. To normally retain the bolt in its outer or locking position, I have provided a helical spring 13, one end 65 of which is secured between the parallel lugs 14 struck out from the case plate 1 and the other end of which abuts the forward end of the cutaway part of the bolt. To normally retain the lever 11 in inoperative position and abutting the spacer 9 above the bolt, I have provided the spring 15 coiled around the spacer 9 below the bolt and having one end abut the lower struck out lug 6, and the other end abut the edge of the lever 11. 75

16 is a rotatable lock hub below the bolt 5 and journalled in the case plate 1 and cover plate 7, this hub having an upwardly extending actuating portion engageable with the lug 17 depending from the bolt. This 80 hub has the aperture 18 therethrough for engagement in by the operating shank of the outside door handle and to facilitate the engagement of the operating shank within the aperture, the entrances of the 85 aperture are flared or inclined inwardly to guide the operating shank thereto.

To lock the bolt 5 from inward movement, I have provided the member 19 journalled in the case and cover plates 1 and 7 respectively above the bolt and adapted to have a wedge engagement with the bolt forward of the pivot. This member has a polygonal aperture for engagement in by a lock operating shank. Specifically, the bolt has in 90 its upper edge the rounded recess 20 which is below the rotatable member 19 and the forward edge of which is in advance of the pivot of the rotatable member so that when the rotatable member is swung through approximately 180°, its periphery comes into engagement with the forward portion of the recess in the bolt preventing inward longitudinal movement of the bolt. To rotate this member from the outer side of 95 the door to lock the bolt, I have provided key actuated mechanism which includes the shank 21 extending into and fitting within 100

105

the polygonal aperture in the rotatable member, the mechanism within the housing or cylinder 22 having an outwardly extending shank provided with a transverse pin 5 which slidably engages in a segmental slot 23 of approximately 180° in the coupling 24 to which the shank 21 is secured by the transverse pin 25. The arrangement is such that the key for actuating the locking mechanism may be rotated through approximately 360° to rotate the member rotatable into wedging engagement with the longitudinally movable bolt.

Another important feature of my invention resides in securing the locking mechanism to the door in such a way that when the door is locked in closed position, the locking mechanism cannot be successfully tampered with. This is accomplished by forming a side of the housing preferably flat and inclined outwardly toward its inner end. Also, this side is corrugated. A suitable dowel 26 extending through the swinging edge of the door and into abutting engagement with the inclined side of the housing holds the locking mechanism within the door. The inclined side is also preferably roughened or corrugated to assist

in more firmly holding the locking mechanism in the door. Thus with this arrangement, when the door is locked in closed position, the holding means for retaining the locking mechanism in the door cannot be tampered with without damaging or destroying the outer side of the door including the panel 27.

What I claim as my invention is:

In a door latch, the combination with a case plate, of a cover plate spaced from the case plate, a locking bolt movable between the case plate and cover plate, a lever between said plates for actuating said bolt, lugs on one of said plates for guiding said bolt, interiorly threaded tubular spacers for said cover plate extending through the case plate and riveted thereto, screws extending through said cover plate and threadedly engaging said spacers, one of said spacers constituting a stop lever, and a coil spring surrounding the other of said spacers having one arm abutting one of said lugs and having another arm abutting said lever and normally holding the latter against the stop.

In testimony whereof I affix my signature.

WILLIAM C. DEVEREAUX.
